UNITED STATES PATENT OFFICE.

FRANK W. SHEAN, OF SAN FRANCISCO, CALIFORNIA.

STREET-RAILWAY TRANSFER-TICKET.

1,026,707.

Specification of Letters Patent. Patented May 21, 1912.

Application filed August 22, 1911. Serial No. 645,338.

To all whom it may concern:

Be it known that I, FRANK W. SHEAN, a citizen of the United States, residing in the city and county of San Francisco and State 5 of California, have invented certain new and useful Improvements in Street-Railway Transfer-Tickets, of which the following is a specification.

The hereinafter described invention relates to an improvement on the form of transfer ticket set forth and described in United States Letters Patent No. 995,917, granted me under date of June 20, 1911. In said Letters Patent the time limit for 10 the use of an issued transfer from a main line railway to all of the transfer points of the branch lines thereof is designated on the conductor punching the transfer on the commencement of the car's run to denote 15 the starting time thereof. However, no provision is made therein for designating the time limit for or the use of the transfer at re-transfer stations, in fact, at present, for re-transferring it is required that a separate 20 transfer ticket be given the passenger. It is this issuing of re-transfer tickets which the present invention obviates, and by so doing providing a transfer ticket not only good for the transfer stations of all branch 25 lines connecting with the main line issuing the same, but equally so at all re-transfer points of the branch connecting lines, and by means of which the time limits for the use of the issued transfer ticket at all trans- 30 fer points to branch lines and all re-transfer points of the said branch lines is indicated directly on the transfer-ticket by the conductor of the main line punching the transfer to note the time of the car's departure 35 at the commencement of its run, and by so doing providing a transfer ticket which shall serve as a common transfer for all the transfer points of the car line issuing the same and for use at all re-transfer points of 40 the branch lines for which the issued ticket is a valid transfer.

By the hereinafter described transfer ticket it is only required that a single transfer be issued to a passenger as a valid transfer 45 for any of the branch lines of the car line from which the transfer is issued and for a continuation of the ride on any of the re-transfer lines of the branch car lines for which the transfer was originally issued, thereby providing against the necessity of the street railway company being required 50 55 60 65 70 75 80 85 90 95 100 105 110

to maintain and issue re-transfer tickets to passengers, inasmuch as a single issued transfer ticket identifies the time limit for the use thereof by a passenger as a valid transfer at all of the transfer points to branch lines and at all re-transfer points of the said branch lines.

To comprehend the invention reference should be had to the accompanying sheet of drawings, wherein—

Figure 1 is a front view of a transfer ticket designed for one of the main lines of a street railway. Fig. 2 is a rear view of the said transfer ticket.

The expression "main" line as hereinafter used, is employed merely to designate the car line originally issuing the transfer ticket, while the expression "branch" lines designates the cross lines to which passengers are entitled to transfer from the "main" car line, the re-transfer lines being those to which the passenger is entitled to ride without extra charge for a continuation of the journey from the "branch" car lines.

In the drawings, Fig. 1 thereof, there is designated a transfer of a "Hayes" street line, which is one of the main lines of the street railway system. On the face of the ticket is a column A, containing the printed street names of all transfer points or branch lines for which a transfer is issued from the Hayes street car line, and at each side of the said column a plurality of columns 1, 2, 3, 4, 5 and 6 are arranged, and within these said columns, in progressive order, are printed numerals indicative of minutes, which appear respectively opposite the successive names of the transfer points, and designate the time limit in minutes after the issuance for which the transfer is good on presentation at any given transfer point. In the left hand columns 1, 2 and 3, the minute numeral indications are from 3 to 40; 13 to 50; and 23 to 57—0 respectively, while in the right hand columns 4, 5 and 6, the minute numeral indications are from 33 to 51; 0 to 10; 43 to 57; 1 to 20; 53 to 58; and 2 to 30 respectively. The minute indications of naught in column 3, and naught to 10 in column 4, and 1 to 20 in column 5 and 2 to 30 in column 6, are printed in red ink; the remaining numerals in each of the said columns being printed in black ink. At the head of the columns 1, 2, 3 and 4, 5, 6, the word "Minutes" is

printed, and immediately above the columns 1, 2, 3, respectively, the numerals 0, 10, 20, and above the columns 4, 5, 6 respectively, the numerals 30, 40, 50, which numerals when punched by the conductor designate the minute time of the car's departure at the commencement of its run.

On the face and at the upper end of the ticket in black ink the numerals 12 and 1 10 to 11 are printed, reading from left to right and immediately beneath the same the numerals 1 to 12 in red ink. These numerals indicate respectively for acceptance the hour time limits within which the transfer must 15 be presented and on the ticket the conventional abbreviations "A. M." for antemeridian and "P. M." for post-meridian are printed. At the bottom portion of the ticket is provided a space in which the months and 20 days of the months are printed, although any well known arrangement for designating the date as to the issuing of the transfer may be employed.

So far the described transfer ticket and 25 its manner of use is the same as that fully set forth and described in the before mentioned Letters Patent No. 995,917, granted unto me on the 20th day of June, 1911, and further detailed description thereof is not 30 deemed necessary.

The back portion of the transfer ticket is divided into a series of spaces 7, 8 and 9, in the present case, a space being provided for each branch line of the main line from 35 which re-transfers are made, these being in the illustrated ticket the Kearny, Larkin, and Fillmore street car lines, and in said spaces is printed the names of all lines to which re-transferring is granted. For an 40 understanding as to the working of the transfer ticket it will only be necessary to follow out the re-transferring from one line, and for this purpose the Kearny street car line will be taken as an example. Within 45 the space 7 is printed the street name of each re-transfer line on which a person transferring from the Hayes street or main car line to the Kearny street or branch car line is entitled to re-transfer privileges for 50 a continuation of the ride, and at the left hand side of said street column a series of parallel columns 10, 11 and 12 are arranged and at the right hand side a similar series of 55 columns 13, 14 and 15, and in said columns are printed numerals indicative of minutes as to the time limits within which the ticket must be presented for re-transfer privilege before and after a given hour. Over each 60 series of the said columns the word minutes is printed, and at the head of the ticket, in black ink, the numerals 12, 1 to 11 are printed, reading from right to left, and below the said row of numerals, in red ink, the numerals 1 to 12 are printed, reading 65 from right to left, the said arrangement of

the parallel rows of numerals being the reverse of similar numerals appearing on the front of the transfer ticket, consequently, the punching of any one of said numerals appearing on the front of the ticket is a 70 punch of the corresponding numeral on the opposite face thereof. With these rows of numerals are associated the conventional printed abbreviations "A. M." for antemeridian and "P. M." for post-meridian, 75 which indications are so printed with respect to the front of the ticket as to register with similar indications appearing thereon. The time limit indications and the arrangement of transfer points on the back of the 80 ticket is the same as the arrangement on the front of the ticket, with the exception that the transfer points on the back of the ticket designate the street lines to which re-transferring is permissible and the time limit for 85 presentation at such re-transfer points.

The working of the invention will be readily understood by the following example, the transfer being issued by the conductor having charge of a car on the Hayes 90 street line, which connects with all associated branch or transfer lines enumerated on the face of the ticket. We will assume the car to have commenced its run, at, say, ten minutes after eleven o'clock, p. m. The 95 conductor punches the numeral eleven of the hour indications at the head of the ticket, also the numeral 12 immediately below, likewise the post-meridian abbreviations P. M., and punches the minute column 2, thus 100 designating that the car left for the commencement of its run at ten minutes after eleven o'clock p. m., and that the same is good on any of the branch lines specified on the face thereof if presented within the time 105 limit noted by the minute indications appearing in the punched column 2. A mere glance at the transfer ticket received by a passenger desiring transfer to the Kearny street car line, conveys the information that the ticket must be presented to the conductor of the Kearny street car by fifteen minutes after eleven o'clock. At the same time the 110 spaces punched by the Hayes street conductor designates on the rear face of the ticket the exact time for presentation of the transfer ticket for the acceptance thereof on any of the associated car lines to which re-transferring is allowed from the Kearny street car line, as, for instance, it must be presented for acceptance to the conductor of the Sacramento street car line not later than twenty-three minutes after eleven o'clock p. m. On presentation to the Kearny 115 street car line, the conductor determines at once if presented within time. If the passenger wishes re-transfer privileges from the Kearny street line, he retains the transfer and delivers the same to the conductor of the car line on re-transferring for a con- 120 125

tinuation of the journey. Thus on the original punching of the transfer is noted thereon the time for presentation at each of the transfer points to all branch lines of the main car line issuing the transfer, and, likewise, the time limits for the use of the issued transfer ticket at each of the re-transfer points for a continuation of the journey on associate car lines of the branch

10 car line.

The described transfer ticket is simple, effective for the described purpose, easily understood by the traveling public, and is a common transfer ticket for all branch lines 15 of the main line and for all associated lines of the branch car lines.

The arrangement of the time limits and the hour and minute departure indications for the car as illustrated are preferred, but 20 any arrangement of time limits or other designations may be employed, the only requirement being that on the departing time of the car being noted on the transfer ticket the time limits for the use of the ticket as a 25 valid transfer at each and every transfer point for branch car lines and re-transfer lines of the branch car lines shall appear automatically.

The minute numerals printed in red ink 30 designate the minutes after the succeeding hour of the punched hour within which the transfer is valid for use at certain transfer points, and the hour numerals printed in red ink indicate the hour succeeding the 35 punched hour indication as to the time of the car's departure. In the example given, the punched numeral 11 designates the hour time of departure, which taken in conjunction with the black printed numerals appearing 40 in the punched minute column indicates that the transfer is valid for acceptance within certain minutes after eleven o'clock. The punched numeral 12, printed in red, designates the succeeding hour of the car's 45 departure, and in case any of the numerals in the punched column of minutes are printed in red ink indicates that the transfer is good and valid at such transfer points within given minutes after the hour of 50 twelve o'clock.

Having thus described the invention what is claimed as new and desired to be protected by Letters Patent is—

1. A street railway transfer comprising a 55 body provided on one face with a plurality of names thereon indicating in sequence the transfer points along the route of the car

from which the same is issued, and on the reverse face provided with a plurality of names thereon indicating in sequence the 60 re-transfer points along the route of a branch line for which the transfer is issued, said body being also provided on each face thereof with a plurality of registering hour indications for punching to denote the 65 hour of departure of the car, and said body on each face thereof being provided with a plurality of registering numerical indications adjacent the names of the several transfer and re-transfer points, the numerical 70 indications opposite any such points indicating when punched in conjunction with the punched hour indication the time limit for the use of the issued transfer at all transfer points to a branch line and for re-transferring therefrom to associated car lines. 75

2. A street railway transfer comprising a body provided on one face with a plurality of names thereon indicating in sequence the transfer points along the route of the car, 80 and on the reverse face thereof with a plurality of names indicating in sequence the re-transfer points along the route of a branch line for which the transfer is issued, said body being also provided on each face 85 thereof with a plurality of registering hour indications thereon for punching to denote the hour of departure of the car at the commencement of its run, and said body being provided on each face thereof with a plurality of registering numerical indications 90 adjacent the names of the several transfer points, the numerical indications opposite any of such transfer points indicating when punched in conjunction with the punched 95 hour indication the time of departure of the car, each indication adjacent the subsequent transfer points noted on each face of the ticket indicating in conjunction with the hour indication punched the time limit for 100 the use of the transfer at such transfer and re-transfer points, and said body being also provided on each face thereof with a table of minute indications thereon adapted when punched to vary the reading of the indications opposite all the transfer points to the 105 extent of the number punched.

In testimony whereof I have signed my name to this specification in the presence of two subscribing witnesses.

FRANK W. SHEAN.
